ROTATABLE WINDOW CONSTRUCTION

Oliver M. Edwards, Syracuse, N. Y., assignor to
 The O. M. Edwards Company, Inc., Syracuse,
 N. Y., a corporation of New York

Application August 29, 1936, Serial No. 98,560

5 Claims. (Cl. 189—64)

This invention relates to window constructions, particularly for vehicles as railway cars, buses, etc., and has for its object a window in which the frame is circular and part-circular sashes mounted in the frame, one being rotatably mounted and having a rotatable opening and closing movement about the axis of the frame into different radial positions.

It further has for its object a window construction in which the rotatable sash frame rotatably mounted with its bearing in the window frame interfits with the window frame by a tongue and groove at the margin of the rotatable sash.

It further has for its object a window construction in which the rotatable part-discoidal or semi-discoidal sash has a marginal portion or frame member complementary to the marginal portion of the rotatable sash or the arcuate sash frame member thereof and also rotatably coacting with the window frame, whereby the rotatable sash has a bearing on the window frame throughout a complete circle.

It further has for its object circular sash frames, at least one of which is rotatably mounted in the window frame, each of the sash frames having transversely extending members or chordal diametrically extending members which normally lap each other, when the rotatable sash is closed.

It also has for its object means for normally locking the rotatable sash consisting of parts carried by the transversely or diametrically extending sash frame member and coacting with the window frame.

It further has for its object a circular window frame mountable in a circular window opening which consists of a split circular body ring and a split circular retaining ring having cylindrical flanges which lap each other and annular flanges which grip on the inner and outer faces of the car body around the window opening, with fastening means coacting with the cylindrical flanges for holding the two split rings assembled and to clamp in the window opening.

The invention consists in the novel features and in the combinations and constructions herein-after set forth and claimed.

In describing this invention, reference is had to the accompanying drawings in which like characters designate corresponding parts in all the views.

Figures 1 and 2 are respectively opposite face views of the window construction, Figure 2 being shown partly in section.

Figure 3 is an enlarged sectional view on lines 3—3, Figure 1.

Figure 4 is an enlarged fragmentary view of this window showing a modified construction of the rotatable sash holder from that shown in Figure 2.

This window construction comprises, generally, a circular window frame, part-discoidal sashes mounted in the frame and complementary to each other, at least one of the sashes being rotatably mounted in the frame and having a rotatable opening and closing movement about the axis of the frame into different radial positions relative to the other sash and the frame.

1 designates the car body formed with a circular window opening 2, the car body having inner 10 and outer walls or face plates 3, 4.

5 designates the window frame, which is a ring, split at 6, this having a cylindrical body portion 7 which extends into the window opening 2 and also an external annular flange 8 and an internal 15 annular flange 9, the flange 8 lapping the margin of the wall of the body around the window opening, that is, it laps the margin of the plate 4. The annular internal flange 9 forms a stop for one of the sash frames.

5^a designates a retaining ring split at 5^b and formed with a cylindrical body portion 10 telescoping over the cylindrical portion 7 of the frame 5 between the cylindrical portion 7 of the frame 5 and the inner wall of the body 1 and also with 25 external and internal annular flanges 11, 12, which lap respectively the inner wall of the plate 3 around the window opening 2, and an internal annular flange on the cylindrical portion 7 of the frame 5. The frame 5 and the retaining ring 5^a 30 are secured together with their flanges 8 and 11 clamped on the outer and inner walls around the window opening, by fastening means coacting with the lapping cylindrical portions, here shown, as screws 14 extending in a direction edgewise of 35 the frame through the lapping cylindrical portions 7, 10. The two parts 5 and 5^a are pressed toward each other, until the screw holes for the screws 14 come into alignment and then the screws are placed in position.

15 and 16 designate respectively upper and lower sashes. These are preferably semi-discoidal and are formed with marginal frames, at least one of which is rotatably mounted in the window frame. Preferably the upper sash 15 is 45 stationary and the lower sash 16 rotatably mounted.

The arcuate frame member 17 of the stationary sash 15 is secured to the window stop flange 9 by screws 19. The rotatable sash member 16 and 50 the window frame are formed with interfitting guide means for the sash, as rib and groove. The arcuate frame member 18 of the lower sash is formed with a channel and the cylindrical portion of the window frame 5 with the rib 20 entering into the channel, the channel having a U-shaped non-metallic or fibrous lining 21 embracing the rib. Also, the lower sash 16 has a semi-circular extension 22 which completes the circle of the arcuate frame member 18 and which is 60

formed with a channel for receiving the rib 20. The frame member 18 and the complementary extension 22 thereof are secured together in any suitable manner. They are here illustrated as 5 secured together by the base 25 of a sash holder secured, as by screws 26, to the diametrically extending rail 27 of the lower or rotatable sash 16 and by screws 28 to the ends of the arcuate extension member 22. A sash holder is however 10 unnecessary, except to prevent opening of the sash from the outside of the car, as the sash being circular will remain in any angular position about its axis.

The sash holder (Figure 2) also includes a 15 movable part, as a latch 30, for coacting with a suitable opening in the window frame, this latch being pivoted at 31 and having a handle 32 arranged in pinch-handle relation to the base plate 25. There is a sash holder at each end of the 20 diametrically extending frame member of the lower sash 16.

In the window shown in Figure 2, the lower sash 15, upon operating of the sash holders, can be rotated in either direction. This is of particular 25 advantage in vehicles, as railway cars, which are hooked into the train, sometimes with one end forward and sometimes with the other end forward.

In Figure 4, a window is shown in which the 30 lower sash 16 is rotatable in one direction only from closed position, and in this case, the base plate 25^a is formed with a lug 25^b which comes against a fixed stop 25^c on the window frame when the lower sash is in closed position. There 35 is a sash holder at each end of the diametrically extending frame member and one presses upwardly against its stop and the other downwardly against its stop. Obviously, upon reference to Figure 4, it will be seen that the lower sash 16 40 can be rotated from closed position only in an anticlockwise direction. This form of latch can be used where the same end of the vehicle is always forward. The diametrically extending members of the sash frames lap each other when 45 the sash 16 is closed, and a suitable weather strip 40 is provided for sealing the joint between the lapping frame members when the rotatable sash 16 is lowered. The only bearing for the rotatable sash 16 is in the window frame in contradistinction to being on a pivot pin. A suitable curtain 50 may be provided, but preferably the glass of the upper sash 15 is colored or darkened to obstruct the glaring light rays.

By reason of this construction, the sash is always 55 tight, when closed, and the rotatable sash rotates without binding when a rotary force is applied thereto.

What I claim is:

1. In a window construction, the combination 60 of a circular window frame, part-discoidal sashes independently mounted in the frame and complementary to each other, one of the sashes being rotatably mounted at the periphery in the frame and shiftable about the axis of the frame into different radial positions relatively to the other sash and the frame, and being entirely free of, 65 and unsecured to the other sash.

2. In a window construction, the combination 70 of a circular window frame, part-discoidal sashes mounted in the window frame and complementary to each other, the sashes having marginal frames,

one of the sashes being rotatably mounted in the window frame and shiftable about the axis of the window frame into different radial positions relative to the other sash and the window frame, the rotatable sash and its frame having interfitting 5 tongue and groove means forming a bearing for the rotatable sash during its rotating movement, the interfitting tongue and groove means having a non-metallic fibrous packing means between them for holding the sash frame and the 10 window frame out of rubbing contact during the rotation of the rotatable sash, the rotatable sash being entirely free of, and unsecured to, the other sash.

3. In a window construction, the combination 15 of a circular window frame, part-discoidal sashes mounted in the window frame and complementary to each other, the sashes having marginal frames, one of the sashes being rotatably mounted in the window frame and having an opening and closing 20 movement about the axis of the window frame into different radial positions relative to the other sash and the window frame, the sash frames including chordal frame members which lap each other when the rotatable sash is in its normal 25 closed position, the chordal member of each sash being entirely free of the chordal member of the other sash and unsecured thereto.

4. In a window construction, the combination 30 with a body formed with a circular window opening, of a window frame consisting of a split ring having a cylindrical portion entering the window opening and an external annular flange for coacting with one wall of the body around the window opening, the cylindrical portion being 35 provided on the inner side thereof with sash guides, and a sash mounted in the window frame and coacting with the guides, and a circular split retaining ring having a cylindrical portion for entering between the cylindrical portion of 40 the window frame and the internal cylindrical wall of the window opening, and external and internal annular flanges lapping respectively the opposite side faces of the wall around the window opening and the window frame, and means 45 including fastening means coacting directly with the cylindrical portion of the frame and retaining ring for securing the cylindrical portions together.

5. In a window construction, the combination 50 of a circular window frame, semi-discoidal sashes mounted in the window frame and complementary to each other, the sashes having marginal frames, each including an arcuate member and a diametrically extending chord member, one of the 55 sashes being rotatably mounted in the window frame and having a rotatable opening and closing movement about the axis of the frame into different radial positions, the chord members of the sash frames lapping each other when the rotatable sash is in its normal closed position, the rotatable sash also having a semi-circular skeleton frame complementary to its arcuate frame member and also rotatably mounted in the window frame whereby the rotatable sash has a 60 bearing on the window frame throughout the entire circle of the window frame, the chord member of each sash being entirely free of, and unsecured to, the chord member of the other sash.

OLIVER M. EDWARDS. 70
